UNITED STATES PATENT OFFICE

91,050

DESIGN FOR AN ICE CREAM CONE

William B. S. Woodward, Brooklyn, N. Y.

Application August 19, 1933. Serial No. 49,061

Term of patent 3½ years

To all whom it may concern:

Be it known that I, WILLIAM B. S. WOODWARD, a citizen of the United States, residing at Brooklyn, in the county of Kings and State of New York, have invented a new, original, and ornamental Design for an Ice Cream Cone, of which the following is a specification, reference being had to the accompanying drawing, forming a part thereof.

I claim:

The ornamental design for an ice cream cone as shown.

WILLIAM B. S. WOODWARD.
